MACHINE FOR TRANSFERRING FLUIDS

Ernest R. Corneil, Niagara Falls, N. Y., and Robert B. Corneil, Toronto, Ontario, Canada

Application March 4, 1938, Serial No. 194,008

3 Claims. (Cl. 230—79)

This invention relates to a machine for transferring fluids, also for separating heavy and light fluids when intermixed.

One object of this invention is to provide a machine which constitutes both a pump and a fluid separator and is useful for several purposes such as transferring either a liquid or a gas or a mixture of liquid and gas from one receptacle to another, for separating a gas from a liquid, 10 for the continuous vaporization of a liquid and either discharge the vapor in its purity or mix it with other vapor or gas so as to form an explosive mixture, for instance, and for pumping air into contact with volatile liquid so as to create 15 and deliver a vapor or gas-mixture thereof.

Another object is to simplify the construction of a machine of this character by eliminating or minimizing the use of glands and of solid or fibrous packings while employing centrifugal 20 force with the liquid being operated upon, or with a relatively heavy liquid that serves only as a liquid-packing or bar to the improper flowing of the lighter liquid or other fluid being operated upon.

Another object is to provide a very simple and effective means to automatically regulate the amount of packing liquid or sealing liquid in the machine, viz., to prevent any excessive accumulation or diminution of the packing or sealing 25 liquid.

Another object is to provide the machine with an elastic rotor-track against which the pumping rotor has rolling contact so as to minimize noise, wear and shocks, and to permit of resisted slip, 30 page at sudden starting and stopping of the means for effecting relative rotary movement of the pumping rotor and the casing that contains the latter.

Another object is to provide, in a machine of 35 this kind, a combination of very few originally separate parts that are of such shape that they can be easily and economically formed of castings that require but little machining, without the necessity for special machine-tool, and which 40 can be assembled quickly and easily by any person of ordinary mechanical ability.

Other objects and important features are pointed out or implied in the following details of description, in connection with the accompanying 45 drawing in which:

Fig. 1 is a view, partly in side-elevation and partly in vertical section, showing one form of our fluid-transferring machine.

Fig. 2 is a view, mostly in side elevation, but 50 partly in vertical section, showing the device of

Fig. 1 mounted on a motor which has its middle part broken out to conserve drawing space.

Fig. 3 is a horizontal sectional view of the device shown in Figures 1 and 4, the section being taken along the line 3—3 of Fig. 4.

Fig. 4 is a vertical sectional view, the section being taken along the zigzag line 4—4 of Fig. 3.

Fig. 5 is a fragmental assembly view, mostly in horizontal section, showing a modified form of the invention.

Fig. 6 is a view, partly in elevation, but mostly in central vertical section, showing another modified form of the invention.

Referring to this drawing in detail, in which, similar reference numerals refer to similar parts 15 in the several views, the invention is described in detail as follows:

In Figs. 1, 2, 3 and 4, the machine consists of a cylindrical casing composed of two primarily separate elements or plane and parallel walls 20 10 and 11, the latter being a centrally apertured disc or cover normally secured in place by screws 12 or other appropriate means, and whose central aperture 13 forms a bearing in which a tubular member 14 is journaled. This tubular member 25 includes an eccentric 15 which is entirely within the casing 10—11 and has an inlet passage 16 and an outlet passage 17, each of these passages having axially-parallel outer portions and radially and oppositely extended inner portions which latter are widened at 18 and 19, as clearly shown in Fig. 3, so as to communicate 30 respectively with several ports that will presently be described.

A tubular hub or driving-shaft connection 20 35 is united with the casing member 2 so as to provide a means for rotating the casing by power from any appropriate source, for instance, from an electric motor conventionally shown at 21 (Fig. 2), the hub 20 being secured to the motor's 40 driving shaft, while the tubular member 14 is secured in a collar 22 by means of a set-screw 23, said collar being an element of a frame that is united with the motor-casing, so that the tubular member 14 is held stationary while the pump-casing 10—11 is rotated by the hub 20 that receives 45 its motion from the motor-shaft. The casing 10—11 also includes an elastic inner surface or track 24.

The pump-rotor 25 is formed with a central 50 cylindrical opening or bearing 26 that constitutes a bearing in which the eccentric 15 is journaled, and is also formed with an annular series of partitions or walls 27 that reach from the bearing 26 to the concave inner surface or flexible 55

and elastic element 24 at the axially remote part of the eccentric; and these partitions separate an annular series of fluid-passages each consisting of a relatively broad and capacious chamber 5 28 and a constricted port 29. A number of these constricted ports are concurrently in open communication with the wide part 18 of the inlet passage while another number of them are in open communication with the wide part 19 of the 10 outlet passage and while others are closed by the convex surfaces at opposite sides of the eccentric 15.

In Fig. 3, the packing or sealing liquid is indicated at 30, and in Fig. 4, the broken line 30 15 indicates the position of the inner surface of the liquid as held by centrifugal force and gravitation when the casing 10-11 is rotated at high speed, being equally distributed around the inner surface 24, so that the eccentrically disposed 20 rotor 25 has some of its partitions 27 deeper in the liquid 30 than those that are opposite and spaced from the inner surface 24, and as rotation of the casing 10-11 is effected around the eccentric 15, some of the partitions move into contact with the surface 24 while others move away therefrom as the rotor rotates with the casing 10-11 and rolls on the surface 24 thereof. To 25 make this rolling contact continuous, the rotor 25 is provided with discs 31 whose peripheries 30 are co-extensive with the outer ends of the partitions 27 and continually bear against the concave surface 24. Any appropriate means (not shown) may be employed for securing these discs to the intermediate part of the rotor so they 35 are parts of the rotor and in close contact with the lateral edges of the partitions 27.

In operation as a gaseous fluid pump, assume that the eccentric in Fig. 3 is held stationary while the casing 10-11 is being rotated in the 40 direction of the curved arrow at the upper-right while the rotor 25 is thereby rotated in the same direction (counter-clockwise) while rolling in the opposite direction on the concave surface or track 24; and during this movement those chambers 28 45 that have the letter "c" therein are compressing the gaseous fluid through the ports connected therewith, while those that have the letter "s" therein are effecting a suction in consequence of the recession of the sealing liquid 30 therein, and the chambers that are indicated at "n" are neutral because they are closed by the eccentric's convex surface. The wide part 18 of the inlet-passage is always in communication with the 50 passages or chambers that are effecting suction, and the wide part 19 of the outlet-passage is always in communication with the chambers that are effecting compression or pressure in consequence of the intrusion of sealing liquid deep into these chambers; so the pumping or transferring of the fluid is continuous 55 during rotation of the casing and rotor around the eccentric. If the direction of rotation is reversed, the inlet and outlet passages are interchanged, and such reversal may be desirable in 60 many cases, as where one kind of fluid has been pumped into a container with another kind of fluid for obtaining a desired mixture and it is desired to pump the mixture from the container into shipping vessels or containers. In thus 65 merely pumping a fluid, it is desirable that the sealing liquid 30 be of such nature that it will not volatilize and mix with the fluid being pumped; for instance, a heavy non-volatile oil or colloid such as one of the petroleum products like or akin to "Petroleum Jelly" or "Vaseline,"

and mercury (though heavy and expensive) 5 may be found useful when pumping certain kinds of liquids or gases. Therefore, where the term "liquid" is used in connection with the sealing element 30, it is used broadly according to the Standard dictionary definition which obviously includes a colloid as well as the thinner liquids.

As a separator of intermixed heavy and light liquids, or intermixtures of liquid and gas, the 10 non-volatile liquid 30 may be eliminated in part or in its entirety; and in lieu thereof, the heavier liquid in the mixture constitutes the sealing liquid, being thrown by centrifugal force against the inner concave surface, as indicated 15 in Figs. 3 and 4, and thus separated from the lighter fluid, as cream is separated from milk in a well known manner; so that as the operation proceeds, the lighter fluid is pressed out through the passages c-19-17, and the heavier liquid 20 tends to accumulate in the casing 10-11; but, to prevent such accumulation, maintain the sealing liquid at a predetermined quantity, and dispose of the surplus, we provide one or more outlets 32 that communicate with the outer air at 25 a point the same distance from the casing's axis as the desired inner limit of the sealing fluid. As here illustrated, the outlet 32 may consist of an L-shaped piece of pipe screwed into the wall 11 so that its free end may be swung to 30 points at different distances from the axis of rotation of the pump-rotor 25 so as to vary the depth or specific quantity of the sealing liquid and thereby vary the pressures produced at any specific speed of the rotor. The overflow or 35 discharge from the outlet 32 can be collected and dispensed or disposed of in any appropriate way and by any appropriate means not here disclosed. This same procedure is employed in the continuous evaporation of a liquid, as where a 40 hydro-carbon is vaporized for mixing the vapor with air and/or other gas or gases in forming a combustion-gas, or explosive mixture of gases.

In the modified forms, Figs. 5 and 6, the parts 45 that are different in construction from those described above, but similar in nature or purpose and function, have the same reference numerals with an added letter, "a" in Fig. 5, and "b" in Fig. 6, for instance, the casing member 10a in Fig. 5 corresponds to the casing member 10 in 50 Figs. 1 to 4; and the corresponding casing-member of Fig. 6 is indicated at 10b.

Though the liquid packing is not shown in Figs. 5 and 6, such is to be used in these modified forms, the same as in the other forms. 55

In Fig. 5, the casing 10a is formed with traction lugs 10c, and if these extend entirely from one to the other of the parallel walls of the casing, notches 31c are formed in the discs 31a to receive the ends of the traction lugs; but as 60 the purpose of these lugs is to form abutments to contact with the partitions 27, they may terminate at the inner surfaces of the discs, in which case, the notches 31c may be eliminated. The eccentric 15a is of such shape that it may 65 cover only two ports 29 concurrently, thereby reducing the number of neutral (n) chambers, and correspondingly increasing the number of compression (c) and suction (s) chambers.

In Fig. 6, the chamber 10b-11b is supported in 70 an axially horizontal position, instead of the axially-vertical position of the other disclosed forms of the invention, and the same is true of the members 15b and 25b. In this form, the inlet 16b and outlet 17b are co-axial with 75

the casing and extend in opposite directions; and at the inlet end, the member 15b is secured to the pedestal 33 by a set-screw 34 like that shown in Figs. 1 and 2; while the casing-member 11b is formed with a tubular journal 11x seated for rotation in a pedestal 33x and is closely fitted against an end of the outlet pipe 17x that is secured in place by a set-screw or by other appropriate means. Rotation of this casing 10b—11b is effected by a flat belt therearound, or a narrow belt or cable in the V-groove 35, or by other appropriate means; but as this type is most useful where a very high speed is employed, a belt or cable in the V-groove 35 and a similar one of a pulley on an electric motor, are most practical.

While the elastic track 24 is desirable under certain conditions, and the traction lugs 10c are desirable under other conditions, there are still other conditions where both may be eliminated, for instance, where the sealing liquid is quite viscous or adhesive so that it adheres to both the casing and the rotor for causing the latter to roll on the concave track under normal working conditions, but permits of relative slipping movement in case of abnormally quick starting, sudden accelerations, etc.

The several illustrated modifications do not exhaust the number of possible or contemplated modifications; so the invention is not limited to the present illustrations and descriptions, for the invention resides in the embodiment of inventive ideas as implied in the foregoing and claimed in the following.

25 What we claim as our invention is:

1. In a machine for transferring fluids, the combination of a cylindrical casing having a concave inner surface and walls which have

plane and parallel inner surfaces, liquid in said casing and adapted to form an annular packing around said concave inner surface, a tubular member journaled in at least one of said walls and comprising inlet and outlet passages and an eccentric through which said passages extend, and a substantially cylindrical rotor having a central bearing in which said eccentric is journaled in the proper relation for keeping the periphery of said rotor substantially in rolling contact with said concave inner surface, said rotor's periphery being formed with radial partitions which divide it into an annular series of fluid passages which have wide and capacious outer ends or chambers and constricted inner ends 15 or ports which latter are adapted to be alternately in and out of open communication with said inlet and outlet passages when relative rotary motion is effected between said eccentric and rotor so that said rotor rolls on said concave 20 surface.

2. The combination defined by claim 1, said inner concave surface being elastic so as to conform to the outer ends of said partitions for the dual purpose of sealing the outer ends of 25 said chambers and providing a flexible track on which said rotor rolls and slips for purposes specified.

3. The combination defined by claim 1, the liquid in said casing being of sufficient depth to 30 completely displace the fluid being transferred or compressed from consecutive chambers, and means to vary the specific quantity of the sealing liquid so that various pressures may be produced in the liquid being transferred, for any 35 specific speed of rotation of the rotor.
